DESIGN FOR A SEWING MACHINE FRAME

William Bishop Foster, Milan, Tenn.

Application July 31, 1944, Serial No. 114,665

Term of patent 14 years

(Cl. D70—1)

To all whom it may concern:

Be it known that I, William Bishop Foster, a citizen of the United States, residing at 407 Broad Street, Milan, in the county of Gibson and the State of Tennessee, have invented a new, original, and ornamental Design for a Sewing Machine Frame, of which the following is a specification, reference being had to the accompanying drawing, forming part thereof.

The figure is a perspective view of a sewing machine frame, showing my new design.

I claim:

The ornamental design for a sewing machine frame, as shown.

WILLIAM BISHOP FOSTER.
